UNITED STATES PATENT OFFICE.

ENOCH A. SWANSON, OF STROMSBURG, NEBRASKA.

DOOR FASTENER.

Application filed October 17, 1927. Serial No. 226,700.

This invention relates to door fasteners, and its general object is to provide a lock for a swinging door, that locks the door in either an open or closed position and retains the same accordingly.

Another object of the invention is to provide a door lock that is key actuated and must be opened by a key from the outside but is capable of being operated from the inside 10 without the key.

A further object of the invention is to provide a lock of the character above set forth, that is extremely simple in construction, inexpensive to manufacture and efficient in operation and service.

This invention also consists in certain other features of construction and in the combination and arrangement of the several parts, to be hereinafter fully described, illustrated in 20 the accompanying drawings and specifically pointed out in the appended claims.

In describing my invention in detail, reference will be had to the accompanying drawings wherein like characters denote like or 25 corresponding parts throughout the several views, and in which:

Figure 1 is a fragmentary elevation taken through a door and its frame, and showing the locking device in applied and locked position.

Figure 2 is a similar view with the door open.

Figure 3 is a sectional view taken through the door and its frame and showing the locking device and door in the positions as shown in Figure 1.

Figure 4 is a similar view and showing the door and locking device as shown in Figure 2.

Figure 5 is a sectional view taken approximately on line 5—5 of Figure 1.

Figure 6 is a detail edge elevation of the key actuated parts and plate carrying the same.

Referring to the drawings in detail, it will be noted that I have illustrated my locking device associated with a door mounted for movement in a horizontal plane but I want it understood that the device can be associated with any type door and frame therefor capable of receiving the same, without departing from the spirit of the invention. The letter A indicates the door frame which is provided with the usual face B and hingedly secured

to one side of the face B for movement in a horizontal plane is a door C of the usual construction.

The locking device is fixed to the frame and door respectively and includes a substantially U-shaped bracket 1 terminating at its ends in apertured ears receiving screws 2 for securing the same to the underside of the top of the frame as best shown in Figure 1 of the drawings. Pivots secured midway the ends of the bracket 1 is one end of an elongated link 3 which pivotally receives at its opposite end 60 a link 4. The link 3 is pivoted adjacent one end of the link 4 and this end has rising therefrom a projection 5 which acts as a stop and engages the link 3 upon one edge thereof as best shown in Figure 4 in order to limit the 65 pivotal movement of the links with respect to each other as well as the movement of the door in its open position as will be readily apparent.

Secured to the door adjacent its free end 75 and in alignment with the bracket 1 is a bearing bracket 6 having a portion 7 bent at right angles upon itself to be disposed in a horizontal plane for pivotally receiving the adjacent end of the link 4. Pivots secured to 80 the underside of the link 4 adjacent its end pivoted to the portion 7 is a latch member 8 extending at right angles to the link 4 and terminating at its outer end in a keeper hook 9 which is provided with an opening 10.

The bearing bracket has cut therefrom and extending at an angle from its fixed end portion as best shown in Figure 4, a tongue 11 which receives one of the ends of a coil spring 12 while the opposite end is secured in an opening 13 formed in the latch member 8. The spring urges the parts to their respective positions as will be apparent, and when the links are manually moved upon movement of the door from their positions as shown in 90 Figures 3 and 4 of the drawings, the spring will exert its tension for further moving the parts accordingly.

Arranged in the path of the notch 14 of the keeper hook 9 is a stud 15 depending from 100 the link 3. The stud is adapted to be received in the notch 14 when the door is disposed in closed position for retaining the latter in said position as will be apparent.

Secured to the door and to the upper reinforcing strip thereof is a bracket 16 having a

free portion bent upon itself to form spaced ears 17 between which is journaled a pulley 18.

The door has arranged and secured there-
5 to adjacent its free edge and in convenient
reach of a person, the key actuated mech-
anism of the locking device, which includes
a plate 19 fixed to said door and having
formed therewith a sleeve 20 extending be-
10 yond opposite sides of said plate with a por-
tion passing through the door as best shown
in Figure 5 of the drawings. Mounted for
rotation in said sleeve is the shank 21 of an
15 arm 22 which is provided with an opening
23. Cut from the plate 19 and curved upon
itself for engagement with the arm 22 is a
tongue 24 which engages the arm 22 and re-
tains the shank 21 in operative position in
20 the sleeve. The free end of the shank 21 ter-
minates inwardly of the outer end of the
sleeve 20 and is formed square in cross sec-
tion to receive a square in cross section
socket formed in the key 25 which is adapted
to rotate the shank and its arm accordingly.
25 Trained in the pulley 18 and having its
respective ends secured to hooks 26 and 27
passing through and secured in the openings
10 and 23 is a flexible element 28. The flex-
ible element as shown is a chain, but of
30 course it can be a rope or other similar ele-
ment.

From the above description and disclosure
35 of the drawings, it will be obvious that I
have provided a door locking device which
will lock the door in either its open or closed
position, and for the purpose of illustrating
40 the operation of the device, assuming that
the door is locked, in its closed position, as
shown in Figures 1 and 3 of the drawings,
the key 25 is arranged in the sleeve 20 to re-
ceive the shank 21, and upon rotating the
45 arm 22 through the medium of its shank, a
pull is exerted upon the flexible element 28
which moves the keeper hook on its pivot
out of engagement with the stud 15 so as to
allow the door to be opened. When the door
50 is arranged to position whereby the links 3
and 4 are disposed beyond their pivot center,
the spring 12 will force the door to its full
open position with the projection 5 of the
link 4 in contacting engagement with the
55 link 3 as best shown in Figure 4. When the
links are in this position, they will retain
the door in its open position, and it is neces-
sary that the pivot of the links be broken
60 before the door can be closed, with the re-
sult the arm must again be moved for mov-
ing the flexible element accordingly, and this
movement will break the links and allow the
door to be closed.

The door can be operated from either of
its positions from the interior thereof, by
merely pulling upon the chain 28 or mov-
ing the arm 22 as will be apparent.

It is thought from the foregoing descrip- 65
tion that the advantages and novel features
of my invention will be readily apparent.

I desire it to be understood that I may
make changes in the construction and in the
combination and arrangement of the several 70
parts, provided that such changes fall with-
in the scope of the appended claims.

What I claim is:

1. A lock of the character described com-
prising a bracket adapted to be fixed to the 75
frame of a door, a bracket fixed to the door,
pivotally secured links pivotally secured to
their respective brackets, a latch member
pivotally secured to one of said links, a
keeper hook formed with said latch member, 80
a projection depending from the other link
and arranged in the path of the keeper hook,
resilient means between one of said brackets
and the latch member, flexible means for
operating the latch member and key actu- 85
ated means connected to said flexible mem-
ber and associated with said door.

2. A lock for swinging doors comprising
a pair of brackets, pivoted links pivotally
secured to said brackets, a pivoted latch 90
member carried by one of said links, and
means for operating said latch member and
including a flexible member having one end
secured thereto, a key actuated means se-
cured to the opposite end and carried by a 95
door.

3. A lock of the character described com-
prising brackets, pivoted links secured to
said brackets, a projection depending from
one of said links, a pivoted latch member se-
cured to the other of said links and adapted
100 to receive said projection, resilient means
between one of said brackets and the pivoted
latch member, a projection formed with the
latch member carrying link and being en-
gageable with the other link, means for
105 moving the latch member on its pivot and
including a flexible member, a pulley for the
flexible member, a sleeve, a square in cross
section shank arranged in said sleeve and
adapted to receive a key for rotating said 110
shank, an arm formed with said shank, and
a hook secured to said arm and receiving the
flexible element.

4. A lock for swinging doors comprising 115
a bracket secured to the frame of a door, a
second bracket secured to the door, links
pivotally secured to each other and to the
brackets respectively, a pivoted latch member
secured to one of said links, a keeper hook 120
included in said pivoted latch member, a
spring having its ends secured to one of said
brackets and the pivoted latch member re-
spectively, a projection depending from one
of said links and arranged in the path of the 125
pivoted latch member for receiving the
keeper hook thereon, and key actuated means
for controlling the movement of the pivoted

latch member against the tension of its spring for operating the latch member and the links as and for the purpose specified.

5. A door lock of the character described comprising a bracket secured to the frame of a door, a bracket secured to the door, an apertured portion formed with the last mentioned bracket, pivoted links secured to the bracket first mentioned and apertured portion respectively, a tongue formed with the second mentioned bracket, a pivoted latch member secured to one of said links, a coil spring having its ends secured to the pivoted latch member and tongue respectively, a pulley carried by said door, a chain trained about said pulley and having one end connected with said pivoted latch member, key actuated means for operating said chain, and projections extending from said links as and for the purpose specified.

6. A door lock of the character described comprising a bracket secured to the frame of a door, a bracket secured to the door, pivoted links pivotally secured to said brackets, a projection carried by one of said links and arranged for engagement with the other link, a projection depending from the last mentioned

link, a pivoted latch member carried by the link secured to the bracket on the door, resilient means between the pivoted latch member and last mentioned bracket, a pulley carried by said door, a plate secured to said door, a sleeve formed with said plate and passing through the door, an arm, a shank formed with said arm and extending into said sleeve, 35 said shank being adapted to receive a key for operating the same, a hook for the pivoted latch member and arm respectively, and a chain trained about said pulley and having its ends secured to the hooks. 40

7. A lock for retaining a door in a closed or open position and comprising brackets, pivoted links pivotally secured to said brackets, a latch member secured to one of said links, a stud depending from the other 45 of said links and arranged in the path of the latch member, spring means for said latch member, key actuated means for operating said latch member, and a projection formed with the latch carrying link and engageable 50 with the other of said links.

In testimony whereof I affix my signature.

ENOCH A. SWANSON.
